UNITED STATES PATENT OFFICE

ARMIN POLLAK, OF BRONX, NEW YORK

LOCK

Application filed July 10, 1928. Serial No. 291,579.

This invention relates to improvements in locks and has particular reference to a lock of the permutation type.

An object of the invention is to provide a highly efficient lock of improved construction embodying features of simplicity and practicability and wherein the locking bolt is effectively maintained, in its locked position, against tampering by unauthorized persons.

Another object is to provide a separable casing for the lock in which the parts thereof are effectively held together in an improved manner while the locking bolt is in operative position, thereby to prevent access to the interior mechanism of the lock.

Another object resides in providing a series of tumblers operable to release a locking mechanism to permit of the retraction of the locking bolt from its operative position and to interpose between and engage with said tumblers and bolt an additional locking element effective, by its engagement with said tumblers when the latter are in certain positions, to prevent movement of said locking bolt.

The above and other objects will appear more clearly in the following detailed description when taken in connection with the accompanying drawings which illustrate a preferred embodiment of the inventive idea.

In the drawings:—

Figure 1 is a fragmentary side elevation, partly broken away and shown in section, of the steering wheel of a motor vehicle showing the application of the invention thereto.

Figure 2 is an enlarged fragmentary elevation, partly broken away and shown in section, of the steering column illustrating the manner in which the lock is attached thereto.

Figure 3 is a plan view of the interior of the lock casing, with parts in section, illustrating the operative position of the locking bolt, the dotted lines indicating parts of the mechanism carried by the cover of the casing.

Figure 4 is an interior plan view of the cover of the casing and parts of the locking mechanism carried thereby.

Figure 5 is a longitudinal section through the lock casing.

Figure 6 is a fragmentary plan view similar to Figure 3 but showing the locking bolt in its retracted or inoperative position.

Figure 7 is a side elevation of one of the tumblers forming a part of the permutation lock mechanism; and

Figure 8 is an end elevation of the tumbler with its spindle shown in section.

Although the lock is shown and described in its application to the steering wheel of an automobile, it will be expressly understood that the construction illustrated herein is applicable to other types of locks without departing from the spirit or scope of the invention as set forth in the appended claims. 65

In Figure 1 there is shown the usual steering wheel 10 having the spokes 11 with the hub of the wheel keyed in the usual manner to the steering shaft 12 which extends through column 13. 70

The lock of the present invention comprises a casing 14 of rectangular formation and provided with a removable cover 15, the casing and cover combining to support and enclose the locking mechanism. 75

The casing 14 carries a sectional attaching sleeve 16 to be secured to the column 13 in the manner best illustrated in Figure 2. The two semicircular sections of the attaching sleeve are held together by means of screw bolts 17 of a special type, which, however, do not form a part of the present invention. These screw bolts are so made that when the same are threaded into their openings and tightened the heads thereof, indicated in 85 dotted lines, will be sheared from the main portion of the bolt by the torsional twist imparted thereto. With the head of the bolt thus detached the outer end of the shank is counter-sunk in a portion of the sleeve 16 90 and thus prevents the bolt from being withdrawn and the sleeve detached from the steering column. One or more bolts 18 similar to the bolt 17 may also be threaded into the sleeve 16 with the inner ends of said bolts 95 projecting through openings in the column 13, whereby turning of the sleeve relative to the column is prevented.

With the lock casing supported in the manner described directly below the steering 100

wheel, the locking bolt 19, which is longitudinally slidable in the casing 14, may have its bifurcated locking end 20 projected from the upper end of the casing so as to receive one of the spokes 11 of the steering wheel between the portions of said end 20 and thereby prevent rotation of said wheel in either direction. When the bolt 19 is locked in this position it is desirable that means be provided for preventing surreptitious removal of the cover 15 of the casing which is only held in its covering position by means of screw bolts 21 (Fig. 3) extending through the cover and bottom of the casing and engaging in a plate 22 carried by the attaching sleeve 16. To avoid the detachment of the cover 15, when the locking bolt 19 is in its operative position, the screw bolts 21 are provided intermediate their ends with squared portions 23 any side of each of which is adapted to engage the adjacent longitudinal edge of the locking bolt whereby a turning movement of the bolt 21 is absolutely prevented. However, said bolts may be removed when the bolt 19 is in its retracted position as shown in Figure 6, by the provision in said edge of the bolt 19 of small recesses 24, each of which aligns with one of the squared portions 23 to afford space for turning movement of the bolt 21.

The permutation locking mechanism comprises a series of tumblers 25, there being three shown in the present instance and these tumblers are carried by the cover 15 with the spindles 26 thereof projecting from the outer side of the cover so that said tumblers may be rotated in accordance with the particular combination necessary to unlock the mechanism. The tumblers, as shown in full lines in Figure 4 and dotted lines in Figure 3, are in position to permit of the retraction of the locking bolt 19 but when said tumblers are turned the peripheries of the heads 26 thereof will each be engaged by an adjacent lug 27 projecting laterally from a locking bar 28, which is interposed between said tumblers and the locking bolt 19. Springs 29 are engaged with the locking bar 28 to urge the same toward said locking bolt, whereby the lugs 30 of the latter are each engaged with an inclined surface 31 of the bar 28 and the shoulder formed by said surface at one end thereof. The bar 28 is mounted in guides 32 for sliding movement laterally of the casing and toward and away from the bolt 19, after the tumblers have been set to the dotted line position shown in Figure 3. The lower end of the locking bolt 19 which projects through the lower end of the casing may now be grasped and pulled downwardly. In so doing the lugs 30 on said bolt will slide along the inclined surfaces 31 and move the bar 28 away from said bolt, the lugs 27 on said bar then entering the notches 33 formed in the heads 26 of the respective tumblers. On the

other hand, when the tumblers 25 are turned so that the notches 33, or any one of them, are not aligned with the lugs 27 the latter will, as previously referred to, engage the peripheries of the heads 26 and thus prevent any lateral movement of the bar 28, with the result that the bolt 19 cannot be pulled downwardly due to the wedging action of the lugs 30 against the inclined surfaces 31.

An additional locking means for the bolt 19 is provided, also controlled by the setting of the tumblers 25. This means consists of a plurality of locking pins or stops 34, slidably carried by the cover 15 and adapted to be recessed within a block 35 on said cover when the tumblers 25 are set in accordance with the proper combination. When in projected position, the pins 34 engage behind a shoulder 36 of the bolt 19, as indicated in dotted lines in Figure 3, thus affording an additional means for preventing retraction of said bolt. In order to retract the pins 34 from their locking positions each tumbler 25, which is utilized to control one of the pins 34, has the inner surface of its head convoluted to provide a number of notches 36 of the same depth and one notch 37 which is greater in depth than the first named notches. The notches of each tumbler are engaged by one end of a locking pin-actuated lever 38, said end being yieldably held in engagement with the notches by a leaf spring 39 carried by the cover 15. The other end of the lever 38 is engaged in a similar manner with the associated locking pin 34 and is designed to project and retract said pin from and into the block 35 as the tumbler 25 is rotated. As long as the first named end of the lever 38 engages in one of the shallow notches 36 of the tumbler the locking pin 34 will be in its projected position and hence behind the shoulder 36 of the bolt 19. However, when said end of the lever engages in the deep notch 37, the movement of the lever is sufficient under the influence of the spring 39 to completely retract the pin 34 into the block 35 and thus move it out of the path of the shoulder 36. When this operation has been accomplished with each of the locking pins 34, notches 33 of said tumblers are aligned with their respective lugs 27, as previously described, and the bolt 19 may be moved to its inoperative position. The purpose of forming the heads of the tumblers 26 with the series of notches 36, rather than having simply a smooth cam surface, is to make it more difficult for an unauthorized person, when turning the spindles 26, to feel the movement of the end of the lever 38 into the deep notch 37.

It will be understood that each tumbler 25 is arranged on its spindle in accordance with a particular number of the known combination so that a person knowing this combination may turn the spindle so as to bring the

deep notch 37 into registration with the end of the associated lever 38. The tumbler is preferably keyed upon the spindle as shown at 40 in Figure 8 so as to turn with said spindle, the locking key being inserted after the tumbler has been rotated relative to the spindle to properly position it in accordance with one number of the combination. To change the combination, it is only necessary to withdraw the locking key and readjust the tumbler about the spindle to a known position.

The person unlocking the lock is enabled to better know the number of notches 36 which are moved past the end of the lever 38, by providing the body of the tumbler with teeth 41 extending about its periphery and engaged by a spring pawl 42, there being one tooth for each of the notches 37. As the tumbler is rotated and each tooth 41 is moved past the free end of its associated pawl the latter will cause a sound to be made which can be heard by the person manipulating the lock.

After the bolt 19 has been unlocked and withdrawn to its inoperative position it may again be moved to locking position by pushing the same upwardly and then turning the tumblers 25 so that the heads 26 thereof will again engage the lugs 27 of the bar 28 and the locking pins 34 again projected into the path of the shoulder 36.

What is claimed is:—

1. In a lock, a sliding lock bolt, a locking mechanism therefor, including a plurality of rotatable tumblers, a locking bar interposed between and engaged with said bolt and tumblers to retain said bolt in locking position, said bar being movable to release said bolt only when said tumblers are rotated to predetermined positions, and a plurality of locking pins also controlled by said tumblers for movement into and out of the path of said bolt.

2. In a lock, a sliding lock bolt, a locking mechanism therefor, including a plurality of rotatable tumblers having notches therein, a locking bar engaging said bolt and having lugs contacting with said tumblers to retain said bolt in locking position, said lugs being movable into said notches to permit release of said bolt only when said tumblers are rotated to predetermined positions, and a plurality of locking pins also controlled by said tumblers for movement into and out of the path of said bolt.

3. In a lock, a sliding bolt, a locking mechanism therefor including a tumbler having a plurality of notches therein one of which is greater in depth than the others, a lever engageable in said notches, and a locking element movable from the path of said sliding bolt when said lever engages in said deeper notch.

4. In a lock, a sliding bolt, a locking mech-

anism therefor, including a tumbler having a sinuous surface forming a plurality of notches, one of which is greater in depth than the others, a lever engageable in said notches, and a locking element movable from the path of said sliding bolt when said lever engages in said deeper notch.

5. In a lock, a sliding bolt, a plurality of tumblers each having notches therein with a notch in each tumbler greater in depth than the remainder, a locking member engaged by said bolt and tumblers and movable relative to the same, when the tumblers are set to predetermined positions, to release said bolt, a lever associated with each of said tumblers and engageable in the notches thereof, and a locking pin for each lever movable out of the path of said sliding bolt when said lever engages in the deeper notch of its associated tumbler.
